WINDOW OR DOOR SCREEN

Filed March 19, 1931

INVENTOR
Charles Allsbury
BY Warren D. House
His ATTORNEY

UNITED STATES PATENT OFFICE

CHARLES ALLSBURY, OF ALBA, MISSOURI

WINDOW OR DOOR SCREEN

Application filed March 19, 1931. Serial No. 523,730.

My invention relates to improvements in window or door screens.

One of the objects of my invention is to provide a novel window or door screen frame which can be easily and quickly adjusted to different lengths and widths, which is cheap to make, is durable, strong, not likely to get out of order, which will hold the screen wire firmly stretched, and which permits the easy and quick replacement of the screen wire when the latter requires such replacement.

The novel features of my invention are hereinafter fully described and claimed.

In the accompanying drawings, which illustrate the preferred embodiment of my invention,

Fig. 1 is a front elevation, partly broken away, of my improved screen.

Fig. 2 is an enlarged section on the line 2—2 of Fig. 1.

Fig. 3 is a perspective view, enlarged, of one of the base members of the screen frame.

Fig. 4 is a similar view of one of the clamping members of the frame.

Fig. 5 is an enlarged plan view of two end portions of two arms of two base members fastened together.

Fig. 6 is an enlarged elevation, partly broken away, of my improved frame in which the arms of the base and clamping members, shown in dotted lines, are connected by extension base and clamping members.

Fig. 7 is a perspective view, enlarged, of one of the extension clamping members, shown in Fig. 6.

Fig. 8 is a similar view of one of the extension base members, shown in Fig. 6.

Similar characters of reference designate similar parts in the different views.

My improved screen frame is provided with four right angled base members 1, each of which, as shown in Figs. 2 and 3, may be right angled in cross section. The base members 1 are arranged in a rectangle with the arms of each member 1 overlapping and lon-

gitudinally adjustable on the adjacent arms of adjacent ones of said base members 1, as shown in Figs. 1, 2 and 5.

Four right angled clamping members 2, which as shown in Figs. 2 and 4, may be channel shaped in cross section, respectively overlie the base members 1, the arms of said clamping members 2 being respectively parallel with the arms which they overlie, said clamping members 2 being disposed and adjustable with relation to each other in the same arrangement and adjustment as has been described with relation to the base members 1.

3 designates usual screen wire held clamped between the clamping members 2 and the base members 1.

Each arm of each base and clamping member is provided with a longitudinal slot 4 which registers with the adjacent slot or slots of the over or underlying arms.

Each arm of each base and clamping member is provided with a hole 5 adapted to register with slots 4 of overlying or underlying arms, and also adapted to register with the holes 5 of over or underlying arms.

6 designates screws which extend through registering holes 5, through registering slots 4 and through the screen wire 3, Fig. 1. Additional screws 7 may also be extended through registering slots 4, as shown in Fig. 1. The screws 6 and 7 are adjustable lengthwise of the slots 4 through which they respectively extend. The screws 7 also extend through the screen wire 3.

The inner end of each screw 6 and 7 has mounted on it a nut 8, Figs. 2 and 5, said nuts bearing against the inner sides of the adjacent arms of the base members 1.

The base members 1 are adjusted on each other to the positions which will make the frame of the proper size. The screen wire 3 cut to size is placed on the base members 1 and the clamping members 2 disposed on the screen wire 3 and overlying the base members 1.

The screws 6 are then inserted, as are the screws 7, through holes 5 and slots 4 which are in register. The nuts 8 are then mounted on the screws 6 and 7 and tightened against the base members 1, the screws being extended through the screen wire 3. The clamping members 2, thus tightly clamp the screen wire 3 against the base members 1, and the screws 6 and 7 hold the screen wire from pulling out from between the members which clamp it.

10 To replace the screen wire, after it becomes worn, the nuts 8, screws 6 and 7 and clamping plates 2 are removed with the worn wire, and new wire is then mounted on the base members and clamped thereto by re-assembling the clamping plates 2, screws 6 and 7 and nuts 8.

If a screen larger than can be formed with the base and clamping members alone, this 20 may be effected by the employment of four straight extension base plates 9 and four extension channel plates 10. The base plates and channel plates are used in pairs.

Each base plate 9 has a longitudinal slot 4' 25 and with two holes 5' respectively adjacent to its ends. The clamping plates 10 are each provided with a longitudinal slot 4' and two holes 5' respectively adjacent to its ends.

To form the frame shown in Fig. 6, the 30 base members 1, shown in dotted lines, are disposed in a rectangle with their adjacent arms spaced apart. Extension base plates 9 are then mounted on the members 1 so as to bridge the spaces between them.

35 The screen wire 3, cut to size, is then placed on the base members 1 and base plates 9. The clamping members 2 are then mounted respectively on the base members 1, as has been described, and the clamping plates 10 are 40 then mounted respectively on the base plates 9, the latter and the clamping plates 10 overlapping the adjacent arms of the members 1 and 2.

Screws 6 are then extended through the 45 holes 5' and the holes 5 or slots 4 of the members 1 and 2 which register with said holes 5'. Nuts are mounted on the screws 6 which are extended through the plates 9 and 10 and members 1 and 2 and through the screen wire 3.

50 Bolts and nuts are assembled in connection with the members 1 and 2, where not covered by the plates 9 and 10, in the manner already described in connection with the form shown in Fig. 1.

55 I do not limit my invention to the structures shown and described, as modifications, within the scope of the appended claims, may be made without departing from the spirit of my invention.

60 What I claim is:—

1. In a window or door screen, an adjustable frame comprising four right angled base members arranged in a rectangle with the arms of each member respectively overlapping and longitudinally adjustable on the

adjacent arms of adjacent ones of said base members, four right angled clamping members respectively overlying said base members with their arms respectively parallel with the arms which they overlie and disposed and adjusted with relation to each other similarly to the arrangement and adjustment of the arms of said base members, said base and clamping members being adapted to clamp between them screen wire, and securing means fastening said clamping and base members together in their adjusted and clamping positions.

2. In a window or door screen, an adjustable frame comprising four right angled base members arranged in a rectangle with the arms of each member respectively overlapping and longitudinally adjustable on the adjacent arms of adjacent ones of said base members, four right angled clamping members respectively overlying said base members with their arms respectively parallel with the arms which they overlie and disposed and adjusted with relation to each other similarly to the arrangement and adjustment of the arms of said base members,

80 said base and clamping members being adapted to clamp between them screen wire, the overlapping arms of said base and clamping members having therethrough holes which

85 register in different positions to which said arms may be adjusted, and fastening devices extending through said holes having means for securely holding said members clamped together in said positions.

90 3. In a window or door screen, an adjustable frame comprising four right angled base members arranged in a rectangle with the arms of each member respectively overlapping and longitudinally adjustable on the adjacent arms of adjacent ones of said base members, four right angled clamping members respectively overlying said base members with their arms respectively parallel with the arms which they overlie and disposed and adjusted with relation to each other similarly to the arrangement and adjustment of the arms of said base members,

95 said base and clamping members being adapted to clamp between them screen wire, the overlapping arms of said base and clamping members having therethrough holes which

100 register in different positions to which said arms may be adjusted, and fastening devices extending through said holes having means for securely holding said members clamped together in said positions.

105 3. In a window or door screen, an adjustable frame comprising four right angled base members arranged in a rectangle with the arms of each member respectively overlapping and longitudinally adjustable on the adjacent arms of adjacent ones of said base members, four right angled clamping members respectively overlying said base members with their arms respectively parallel with the arms which they overlie and disposed and adjusted with respect to each other similarly to the arrangement and adjustment of the arms of said base members,

110 said base and clamping members being adapted to clamp between them screen wire, each of the arms of said base and clamping members having a longitudinal slot which registers with the slots of adjacent arms, and clamping means extending through said slots and

115 movable lengthwise thereof for fastening said members together.

120 4. In a window or door screen, an adjustable frame comprising four right angled base members arranged in a rectangle with the arms of each member respectively overlapping and longitudinally adjustable on the adjacent arms of adjacent ones of said base members, four right angled clamping members respectively overlying said base mem-

125 bers with their arms respectively parallel with the arms which they overlie and disposed and adjusted with relation to each other similarly to the arrangement and adjustment of the arms of said base members,

130 said base and clamping members being adapted to clamp between them screen wire, the overlapping arms of said base and clamping members having therethrough holes which

bers with their arms respectively parallel with the arms which they overlie and disposed and adjusted with respect to each other similarly to the arrangement and adjustment of the arms of said base members, and securing means fastening said clamping and base members together in their adjusted positions, and screen wire clamped between said clamping and base members and engaged and held by said fastening means.

In testimony whereof I affix my signature.
CHARLES ALLSBURY.
